J. H. TROMANHAUSER

CONCRETE CRIB

Filed Nov. 7, 1925

UNITED STATES PATENT OFFICE.

JESSE H. TROMANHAUSER, OF TORONTO, ONTARIO, CANADA.

CONCRETE CRIB.

Application filed November 7, 1925. Serial No. 67,584.

This invention relates to hollow concrete cribs of a type adapted to be floated to a predetermined position and there sunk and filled with solid materials. Such cribs have 5 usually been provided with strong, solid concrete bottoms which rest on the sea bottom. If, however, the sea bottom be not level, the contact of the crib bottom therewith is not continuous and spaces are left 10 not filled with solid material. Further, it is not feasible with such a crib to drive piles within the confines of the crib as is sometimes desirable for purposes of anchorage and for foundations. My object, therefore 15 is to devise a crib bottom construction which will enable the crib filling to follow the sea bottom contours, and which will permit piling to be driven within the confines of the crib if necessary. Such a bottom, 20 preferably should possess the following characteristics:

It must be watertight and adapted to withstand the hydrostatic pressure when the crib is floating.

25 It must be thin enough to crush down under the weight of the crib filling when not supported.

It should be thin enough so that piles may be driven through it when desired.

30 It should, when broken down, come away freely from the crib wall footings, so that no damage is done to the latter, and so that the whole bottom may be lifted out if desired.

35 I attain my object by first forming a concrete bottom slab, and then casting the wall footings of the crib over the edges of the slab in such a manner that, though the joints formed are substantially watertight, 40 the bottom may be readily broken out of the rabbets so formed when the need arises. Before the finished crib is floated on its own bottom, a wooden backing is applied above the bottom, which is braced from the 45 side walls in the manner hereinafter described and illustrated in the accompanying drawings in which—

Fig. 1 is a plan view of part of a crib constructed in accordance with my invention;

50 Fig. 2 a vertical section, partly broken away, taken on the line 2—2 in Fig. 1; and

Fig. 3 a similar view taken on the line 3—3 in Fig. 1.

In the drawings like numerals of reference 55 indicate corresponding parts in the different figures.

In constructing a hollow concrete crib according to my invention, I first cast a reinforced concrete slab 1, which slab will 60 form the crib bottom.

In practice, of course, a large crib will be of cellular construction, that is, divided into compartments by transverse and longitudinal walls. For the purpose of the present 65 specification it may be assumed, however, that the crib is of simple construction provided only with four side walls, since in such a simple construction may be embodied all the features of my invention. 70

The concrete bottom slab 1 having set, the walls 2 are cast with their footings 3 overlapping the edges of the slab as shown. In order to ensure that the bottom may be broken out of the rabbets in the footings, 75 which result from the process of manufacture and, at the same time to ensure that the joints between the bottom slabs and the footings are watertight, I preferably coat the margins and edges of the bottom slab with tar or any like substance which 80 will function in the manner desired. When the crib is completed and, before it is floated on its own bottom, a backing, preferably of wood, is applied above the bottom, which is braced from the side walls. 85 This backing is preferably constructed as follows:

A wooden back 4, which may be of, say, 2" plank, is applied directly to the upper 90 surface of the bottom slab 1. On this are superimposed one or more cross bars 5, preferably of heavy timber. On each cross bar is secured a block 6. Against the opposite ends of this block bear the diagonal braces 95 7, the other ends of which bear against opposite walls of the crib which are preferably notched to provide shoulders for engagement with the ends of the braces. Between the ends of one or both braces and the block 6, 100 wedges 8 are driven to tighten the lower ends of the braces firmly against the cross bars to properly brace the bottom against the upward hydrostatic pressure when the crib is floated. A lever 9 is preferably introduced between the wedges 8 and the end of the block 6 to facilitate the loosening of the braces when the bottom is to be broken 105

out, the lever being readily removable by an upward pull on its outer end, which may be effected in any suitable manner.

When the crib is completed, it is floated 5 to the desired location and sunk. The bottom may be crushed upwardly by projections at the sea bottom or conversely may be crushed downwardly into any depressions by the weight of filling deposited in the crib. 10 The bottom being thin, it may be readily pierced by piles, if desired, while from the nature of the joint between the bottom and the walls, the bottom slab may be broken cleanly away from the side walls and lifted 15 out in pieces.

From the above description it will be seen that I have devised a process of manufacturing hollow concrete cribs and have developed a construction which will satisfactorily attain the objects of my invention as 20 set out in this specification.

What I claim is:

1. A process of forming hollow concrete cribs which consists in forming a thin concrete slab and, after the slab has set, casting 25 the crib walls thereon with only a portion of the footings adjacent their edges overlying the margins of the slab.

2. A process of forming hollow concrete cribs which consists in forming a thin concrete slab and, after the slab has set, applying 30 a tar-like coating to the edges and the margins of the upper surface slab; and casting the crib walls on said slab with only a 35 portion of the footings adjacent their edges overlying the margins of the slab.

3. A hollow concrete crib having the footings of its walls formed with downwardly facing rabbets; and a separate relatively fragile 40 bottom slab having its margin fitting in said rabbets.

4. A hollow concrete crib having the footings of its walls formed with downwardly facing rabbets; a separate relatively fragile 45 bottom slab having its margin fitting in said

rabbets; and a removable backing secured against the upper surface of the slab.

5. A hollow concrete crib having the footings of its walls formed with downwardly facing rabbets; a separate relatively fragile 50 bottom slab having its margin fitting in said rabbets; a backing member applied to the upper surface of the slab; and removable braces bearing against the walls and said backing member. 55

6. A hollow concrete crib having the footings of its walls formed with downwardly facing rabbets; a separate relatively fragile bottom slab having its margin fitting in said rabbets; a cross bar crossing the back 60 of said slab; and removable braces bearing against the walls and said cross bar.

7. A hollow concrete crib having the footings of its walls formed with downwardly facing rabbets; a separate relatively fragile 65 bottom slab having its margin fitting in said rabbets; a removable back applied to the upper surface of the slab; a cross bar engaging the backing; and removable braces bearing against the walls and cross bar. 70

8. A hollow crib having walls of reinforced concrete formed with downwardly facing shoulders adjacent their lower edges; and a separate relatively thin bottom of reinforced concrete having its margin engaging 75 said shoulders and having a watertight frangible seal with said walls.

9. A hollow crib having walls of reinforced concrete formed with downwardly facing shoulders adjacent their lower edges; 80 a separate relatively thin bottom of reinforced concrete having its margin engaging said shoulders and having a watertight frangible seal with said walls; and a removable backing secured against the upper 85 face of the bottom.

Signed at Toronto, Canada, this 22nd day of Oct., 1925.

JESSE H. TROMANLAUSER
